Des. 191,044
Patented Aug. 8, 1961

191,044

PORTABLE AIR PURIFIER AND OZONIZER COMBINATION OR SIMILAR ARTICLE

Edward S. Cornell, Jr., 9 Winding Lane, Westport, Conn.

Filed Oct. 12, 1959, Ser. No. 57,914

Term of patent 14 years

(Cl. D16—2)

Des. 191,044

PAGE 2

Fig. 3.

Fig. 4.

FIG. 1 is a rear perspective view showing the right end and top of a portable air purifier and ozonizer combination, or similar article embodying my new design; and

FIG. 2 is a front perspective view showing the front, left end and top thereof.

FIG. 3 is a front elevation thereof.

FIG. 4 is an enlarged perspective view partially in section, showing the configuration of the filter panel thereof.

The dominant features of my design reside in the full line portions of the drawings.

I claim:

The ornamental design for a portable air purifier and ozonizer combination or similar article, as shown and described.
